Bert Mills,

Attorney

UNITED STATES PATENT OFFICE.

BERT MILLS, OF OROVILLE, WASHINGTON.

PACKAGE-TIE.

1,280,064.

Specification of Letters Patent. Patented Sept. 24, 1918.

Application filed February 20, 1918. Serial No. 218,300.

To all whom it may concern:

Be it known that I, BERT MILLS, a citizen of the United States, residing at Oroville, in the county of Okanogan and State of Washington, have invented new and useful Improvements in Package-Ties, of which the following is a specification.

This invention relates to new and useful improvements in package ties and the principal object of the invention is to provide a device of this nature with means for firmly gripping the cord.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 shows my invention in use on a package.

Fig. 2 is a longitudinal section through the device.

Fig. 3 is a detail view of the spring.

As shown in these views the device is formed of a metal plate 1 of substantially rectangular form but having its edges slightly curved so that the corners thereof are slightly tapered. Two of these corners are turned upwardly to provide the hooks 2 and 3. The third corner is turned upwardly to provide the hook 4 and the side edges of this hook are extended as shown. The fourth corner has its side edges turned upwardly and slightly curved to provide a pair of ears 5 spaced apart. The plate is slightly curved downwardly at each corner as shown in Fig. 2 and the center thereof is provided with a depression 6. 7 is a pin having its lower end secured centrally in

this depression and at its upper end said pin is firmly secured to a disk 8. 9 indicates a second disk loosely arranged on the pin and fitting in the depression. These disks are slightly concave with the convex portions opposite each other. 10 indicates a spring plate preferably of the form shown in Fig. 3 and this spring plate is also loosely arranged on the pin and under the disk 9. The arms 10' of the spring plate are bent downwardly so that the central part 10* will engage the disk 9 and hold said disk against the upper disk.

In using the device the cord 11 has one end connected with the hook 4 and the device is placed on the package held in the left hand with the thumb of the left hand placed on the upper disk and the corner provided with the ears 5 nearest the farthest edge of the package. The string is then passed lengthwise around the package and over the hook 3, then back again lengthwise of the package into engagement with the hook 4 and from this hook the string is passed through the space between the ears 5 and then under the package to the hook 2, then back under the package to the slot 5 and then the string is placed between the two disks which will grip the cord and prevent the same from slipping.

In this manner the cord is securely held around the package without tying and the package may be thrown about without the cord becoming untied. The cord may be quickly and easily removed from the package and the device may be used over and over again.

It is thought from the foregoing description that the advantages and novel features of my invention will be readily apparent.

I desire it to be understood that I may make such changes in the construction and in the combination and arrangement of the several parts, provided that such changes fall within the scope of the appended claims.

What I claim is:—

1. A package tie comprising a rectangular plate, a hook formed at each corner thereof, a depression in the central part of said plate, a pin secured in said depression, a

100

spring plate loosely mounted on said pin and arranged in the depression, a disk located above said spring plate and loosely mounted on the pin, and a second disk firmly secured to the end of the pin.

2. A package tie comprising a plate, the metal at one corner of which is bent up-

wardly to form a pair of ears with a space between them and the other corners being turned upwardly and inwardly to form 10 hooks, and a tension device carried by the central part of said plate.

In testimony whereof I affix my signature.

BERT MILLS.
